UNITED STATES PATENT OFFICE.

LUIGI F. MAZZETTI, OF NEW YORK, N. Y.

DESIGN FOR AN ICE-CREAM MOLD.

SPECIFICATION forming part of Design No. 14,327, dated September 25, 1883.

Application filed August 3, 1883. Term of patent 7 years.

To all whom it may concern:

Be it known that I, LUIGI F. MAZZETTI, of the city, county, and State of New York, have invented and produced a new and original Design for Ice-Cream Molds, of which the following is a specification.

Reference is to be had to the accompanying drawings, forming part of this specification, in which similar letters of reference indicate corresponding parts in both the figures.

Figure 1 is a plan view of my newly-designed ice-cream mold, shown with the cover removed. Fig. 2 is a side elevation of the same, partly in section, these two views being deemed necessary to fully illustrate my design.

In the drawings, A represents the body, and

B C the top and bottom, said parts being of oblong form with curved ends. The parts B C have edges projecting beyond the body A, and parallel to each of said projecting edges, 20 and in close proximity thereto, is a double rib, the whole presenting to the eye an agreeable and attractive form.

Having thus described all that is necessary to a full understanding of my invention, what 25 I claim as new is—

A design for an ice-cream mold, substantially as shown and described.

LUIGI F. MAZZETTI.
